CASE FOR A CHECK ENCODER

James W. Jacobson, Saint-Nom-La-Breteche, France, and
Richard G. Clayton, Detroit, and Jerry J. Sims, South-
field, Mich., assignors to Burroughs Corporation, De-
troit, Mich.

Continuation-in-part of design application Ser. No.
395,276, Sept. 7, 1973. This application Mar. 6,
1975, Ser. No. 555,960

Term of patent 14 years

Int. Cl. D14—02

U.S. Cl. D64—11 C

FIG. 1.

FIG. 2.

FIG. 1 is a front perspective view of a case for a check encoder showing our new design; and

FIG. 2 is a rear perspective view thereof.

This is a continuation-in-part of design application Ser. No. D. 395,276, filed Sept. 7, 1973.

We claim:

The ornamental design for a case for a check encoder, substantially as shown and described.
